BLOW-OFF TANK FOR STEAM BOILERS

Price M. Greenlaw, Washington, D. C.

Application April 13, 1934, Serial No. 720,465

3 Claims. (Cl. 122—379)

This invention relates to clean-out devices or systems for steam boilers and particularly to a device commonly recognized as a blow-off tank.

It is well recognized in the art that steam boilers accumulate considerable sediment over the inner surfaces, caused to be deposited thereon by chemical changes in the water and unless this deposit is removed at frequent intervals, serious damage with its attendant danger will result.

Many attempts have been made to provide satisfactory means for permitting a frequent blow-off or clean out of the boiler, necessitating highly expensive equipment, as a result of many municipal regulations, since the blow-off cannot be directed to the atmosphere nor directly to a sewer.

It is a purpose of the present invention to provide a tank so arranged as to permit the blow-off pipe from the boiler to discharge directly therein with a minimum of noise and the complete absence of objectionable vapors.

A further object resides in the provision of a device so constructed as to receive the discharge from the boiler blow-off and to conduct such blow-off products therethrough in such manner as to permit their final discharge directly to a sewer, drip pan or the like.

In prior devices, great difficulty and expense has been encountered in finding a suitable and lawful discharge for the steam vapors from the blow-off and in many cases, especially in crowded communities, it has been necessary to provide a pipe line from the blow-off tank to the roof of the structure, often requiring many bends and joints in the line. In such cases it has been found that the joints or bends of the line have gradually become clogged up with an accumulation carried upward by the escaping steam, and when this condition exists, great danger of explosion is present in the blow-off tank, since these tanks are not ordinarily constructed to withstand boiler pressure. To avoid this highly dangerous condition, the present invention aims to provide means forming a vent for the steam, of such length as may amply be contained in the boiler room, and further to provide means for condensing such steam as may enter the vent, returning the products of condensation back to the tank.

A further object of the invention resides in the extreme simplicity of the device, embodying unusual features of safety as will permit the installation of the device in municipalities having strict regulations.

Another and important object is the extreme

cheapness of manufacture and installation, its durability and highly efficient action in use.

Other important objects and advantages of the invention will present themselves during the course of the following description, reference being had to the accompanying drawing, in which,

Figure 1 is a longitudinal section through a device constructed in accordance with the invention and,

Figure 2 is a transverse section on line 2—2 of Figure 1.

Like numerals refer to like parts throughout.

In the drawing, the numeral 5 designates a metallic tank, preferably of cylindrical form. The tank 5 is formed of suitable heavy gauge sheet metal, having ends 6 and 7, welded or otherwise secured thereto. A man-hole 8 is provided in the end 6 to permit access to the interior of the tank. The tank is preferably supported in spaced relation to the floor as indicated at 9. Leading into the tank 5 preferably centrally thereof, is a blow-off pipe 10 from the boiler, not shown, and having a cut-off valve 11. Leading from the tank at the opposite end 7, is an overflow pipe 12. The pipe 12 is of a size approximately four times the diameter of the pipe 10, and as clearly shown has its inner end 13 turned downward and terminating in spaced relation to the bottom of the tank. The outer or free end 14 may be directed to a convenient sewer connection or into a suitable drip receptacle.

Means are provided to remove any accumulated sediment from around the inlet end 13 of the pipe 12, comprising a blow-off pipe 15 having communication with the interior of the tank through an opening 16, that is concentric with the open end 13. A cut-off valve 17 controls the discharge through the pipe 15. The pipe 15 has connection with the discharge end 14 of pipe 12 as shown at 18. It should be noted that in the system of discharge, there are no abrupt joints or other points that might tend to accumulate sediment. As clearly shown, the pipe 12 passes through a suitable coupling in the end 7 and the position of the pipe is such as to maintain a level of water in the tank on a line approximately with the inner end of the pipe 10.

Arranged near the end 6 and projecting in a vertical position is a combined vent and condensation stack 19. This stack has communication with the interior of the tank through an opening 20 and has its upper end formed entirely open, with the exception of a supporting spider 21, adapted to receive and centrally position a

water supply pipe 22 having a spray head 23 downwardly directed. A cut-off valve 24 is positioned in the pipe 22 convenient for operation and preferably arranged adjacent the valve 11, 5 since it is essential that both valves be operated simultaneously. The stack 19 is of a size approximately five times the diameter of the pipe 10, although it should be understood that there is no restriction on size. The stack is of a height 10 such as may conveniently terminate within the boiler room, thus avoiding the necessity of conducting it to the exterior of the building.

A baffle plate 25 having reinforcing angle irons 26, is arranged within the tank about in a position intermediate the ends 6 and 7. The plate 25 is arranged at an angle of approximately 20 degrees from the vertical. As shown clearly in Figure 2, the upper portion of the plate 25 is shaped to conform to the curvature of the tank, 20 and completely separates the upper half of the tank into separate air chambers. The lower or straight edge of the plate terminates a few inches below the normal surface of the water, leaving a relatively large passage therebelow for the passage of the water to the drain. Primarily, the 25 object of this plate 25 is to provide a means for retarding the velocity of the incoming water and steam from pipe 10, and this is accomplished by the fact that as the steam and water enter from pipe 10, they engage the surface of the tank water, causing it to roll and dash against the baffle. This action not only retards the velocity of the water, but reduces to a minimum the noise 30 that would naturally be present, but for this arrangement. A vent pipe 27 leads from the interior of the stack 19 to the top portion of the pipe 12 in order to avoid the possibility of the pipe 12 serving as a siphon.

The operation of the device is as follows:—
40 The device having been set up and filled to the normal level of the overflow with water from the pipe 22, the system is now in condition for operation.

Valves 11 and 24 are now opened, which action 45 permits the entry into the tank 5 of boiling water and steam from the boiler blow-off 10, carrying with it any accumulated scale or other sediment that has settled therein. The opening of the valve 24 permits the entry of pure water from 50 the main supply which enters the stack 19 as a spray from the head 23. Since the pipe 10 enters the tank at normal water level, the incoming water and steam from the boiler will engage the surface of the tank water causing it to roll and 55 dash against the baffle plate 25. This action materially reduces or retards the velocity of the incoming water and steam and its engagement with the baffle plate throws the water in a reverse direction. This reverse movement not only 60 aids in reducing velocity, but further serves to reduce to a minimum the natural rumbling or churning sound usually present in other devices. During this rolling or dashing of the water, much moisture in vapor form is created 65 with a consequent release of its heat content, and such vapor together with the incoming steam tends to escape through the stack 19, where its passage upward is intercepted by the spray 23. The spray thus condenses such vapor and the 70 resultant water drops back to the tank 5. The spray thus has a dual purpose, namely, to condense the escaping vapors and to furnish a pure water supply for the tank that will counteract the pitting action of the boiler water, thereby 75 greatly prolonging the life of the tank.

During the blow-off period of the boiler, the tank 5 will rapidly fill with water to a point near its top. Upon the closing of the valve 24 and valve 11 the tank will automatically drain to its normal water level through the overflow pipe 12, carrying with it the major portion of the deposited scale or sediment from the boiler. Since the end 13 is downturned as indicated, the discharge of the water will occur at a single point. Such action will naturally create a slight deposit 10 at this point much in the shape of a doughnut around the inlet to the end 13, and it becomes necessary from time to time to remove this accumulation. To accomplish this the valve 17 is 15 opened and the water normally remaining in the tank will carry such sediment accumulation through the pipe 15. It becomes necessary from time to time to clean the entire inner surface of the tank and this may be accomplished by a removal of the man-hole cover 8. The baffle 25 is 20 also accessible through the man-hole and from this point may be repaired or renewed.

It will be obvious from the foregoing that an extremely simple and efficient form of mechanism 25 has been constructed to accomplish a purpose that has heretofore proven expensive and disagreeable as to noise of operation. The structure may be set up adjacent a steam boiler with the vent stack of such length as to terminate within the boiler room, thus avoiding the expense of carrying the vapor discharge to the roof of the building. The discharged or overflow water emerges from the tank free from steam or vapor and is of low heat content and in this condition it is permissible to direct it into a convenient sewer trap or receptacle. The device is safe to a high degree, presenting little or no possibility of danger to the operator or system. Should the operator fail to open valve 24, his attention will be immediately directed to the fact by the issuance from the 30 stack 19 of steam and vapor. It may be found desirable in some cases to position water circulating coils in the lower part of the tank 5 as a means of aiding in the heating of feed water for the boiler and a further reduction in the heat 35 content of the tank water.

It is to be understood that the invention is not limited to the precise arrangement shown, but that it includes within its purview whatever changes fairly come within the terms or spirit 40 of the appended claims.

Having described my invention, what I claim is:

1. A blow-off device for steam boilers comprising an elongated cylindrical casing having closed ends, a blow-off pipe from a steam boiler leading 55 into one end, an overflow pipe leading into the casing from the opposite end and having a downturned end, a vent stack for the casing adapted to vent the steam vapors from the blow-off water discharged into the cylindrical casing, vapor 60 condensing means arranged in said stack, vent means for the said overflow pipe exteriorly of the casing, a baffle plate in said casing arranged in the path of travel of the incoming blow-off products and drain means for the casing. 65

2. A device of the character described comprising a cylindrical metallic tank having closed ends, a blow-off pipe leading into the tank at one end and a water level and overflow pipe leading into the opposite end, said overflow pipe having an 70 inner downturned end slightly spaced from the bottom of the tank, vent means for the overflow pipe exteriorly of the tank, a vent stack for said tank open at its upper end, a spray device positioned in said stack centrally thereof, a baf- 75

file plate positioned in said tank intermediate its ends and a sediment drain device for the tank positioned adjacent the downturned end of said overflow pipe.

- 5 3. A structure of the character described comprising an elongated cylindrical tank having closed ends, a pipe leading into one end of the tank and having connection with the blow-off coupling of a boiler, a valve for controlling the
10 flow through said pipe, a water level and overflow pipe leading into the tank from the opposite end and having its inner end curved downward and terminating in spaced relation to the bottom of the tank, a vent stack of relatively large diameter having an open upper end and communicat-

ing with the interior of the tank, a water pipe leading into the upper end of the stack and held in a centralized position, a spray head carried by said water pipe and likewise positioned in said stack, a vent for said overflow pipe, a sediment drain pipe for the tank communicating with the interior of the tank through an opening concentric with the downturned end of the overflow pipe, a baffle plate arranged in said tank intermediate its ends and positioned at an angle from the vertical, the lower edge of said baffle spaced from the bottom of the tank and a man-hole opening formed in one end of the tank.
